UNITED STATES PATENT OFFICE.

EUGENE I. BLOUNT, OF CAMBRIDGE, MASSACHUSETTS.

PNEUMATIC DOOR-CHECK.

SPECIFICATION forming part of Letters Patent No. 289,380, dated December 4, 1883.

Application filed May 19, 1883. (Model.)

To all whom it may concern:

Be it known that I, EUGENE I. BLOUNT, of Cambridge, county of Middlesex, State of Massachusetts, have invented an Improvement in 5 Door-Checks, of which the following description, in connection with the accompanying drawings, is a specification, like letters on the drawings representing like parts.

My invention relates to a door-check or apparatus for automatically closing the door without slamming it; and it has for one of its objects to enable the movements of the door to be more perfectly controlled than by the devices heretofore employed.

15 The invention is embodied in an apparatus having an actuating-spring and an arm operated thereby with an oscillating movement when the door is opened or closed, the said arm being connected, as hereinafter described, 20 with the door and with a controlling or cushioning cylinder, to retard and regulate the movement of the said arm in closing the door. The end of the arm is connected with the door by jointed levers or connecting-rods, and 25 means are provided for adjusting the strength of the spring when desired, and also for adjusting the cushioning effect of the cylinder, which contains a fluid and a piston, provided with a valve, allowing the fluid to pass through 30 it when moving in one direction through the cylinder, as in opening the door, the said valve closing and causing the fluid to be forced around from one to the other end of the cylinder through a suitable passage controlled by 35 a valve in the return movement of the said piston as in closing the door. The piston has a piston-rod connected with the spring-pressed arm that operates on the door, and the connections are so arranged that the leverage of the arm or power of the spring acts with least advantage when the door is widest 40 opened, thus causing a rapid movement of the door when it begins to close, the resistance of the fluid at the same time operating with the least advantage, and as the door closes the leverage of the spring increases as well as the force derived from the resistance of the fluid in the cylinder, so that the door is finally closed with a slow but powerful movement.

Figure 1 is a plan view of a door-check embodying this invention; Fig. 2, a partial horizontal section thereof, showing the construction of the cushioning cylinder and piston and the actuating-spring; and Fig. 3, a partial vertical section on line $x-x$, Fig. 1.

The main actuating-spring a , shown as a spiral spring similar to those employed for driving trains of wheel-work, is inclosed in a case, b , having a foot or plate, b' , by which it may be fastened upon the casing of a door, 60 over the top of the door, a short distance from the hinge, as shown in Fig. 1. One end of the spring a is connected with the case b , as by the screw 2, and the other end is connected with a collar, c , provided with a groove, 3, 65 to receive a pin or key connected with the spindle d , passing through the said case and provided with a ratchet, d' , at one end, adapted to receive a key or wrench at its other end. The cover b^2 of the spring cylinder or case b 70 has, in this instance, made as a part of it one of the heads e of the regulating or cushioning cylinder f . The door-actuating arm h is forked to embrace the case b , it being pivoted to turn loosely upon the spindle d at either 75 side of the said case, and being provided with a pawl, i , to engage the ratchet d' , causing the said spindle to turn with the arm h when moving in the direction of the arrow 4, Fig. 1, and thus through the collar c to strain the 80 spring a .

By turning the spindle d by means of a crank or key, the initial force of the spring a may be regulated as desired, and it will be seen that the force of the spring will always tend to turn 85 the arm h in the direction opposite to the arrow 4. The end of the arm h is connected by toggle-jointed levers $k k'$ with the door, the said lever k' being pivoted at 5 in a lug, m , fastened upon the door near the end of the arm 90 h when the door is closed, as shown in full lines, Fig. 1. As the hinge pintle or axis of the movement of the door does not coincide with the spindle d or axis of the movement of the arm h , the levers $k k'$ separate as the door 95 opens, and the distance of the point 5 from the spindle d or fulcrum of the arm or lever h will gradually increase, thus diminishing the lever-

age of the spring a , although the force of the said spring will increase as it is being wound up by the movement of the arm h . A lateral projection, h' , on the arm h has an adjustable stop, h^2 , for the lever k , causing the force of the spring to be applied through the lever k' to the door, instead of merely swinging the said levers around on their pivots into line with one another, as would happen if the pivotal movement of the lever k on the arm h were not arrested, and in operation the arm h and lever k move together as if both consisted of a single piece, except when, in opening the door to its fullest extent, the lever k' may be arrested, and the lever k will then draw away from the arm h ; but in many instances the arm h and lever k may be made in a single piece.

The lug m is also provided with a preferably yielding stop, m^2 , which engages the lever k when the door is sufficiently opened, thus preventing further movement of the lever k' , and causing the lever k to turn on its joint with the arm h away from the stop h^2 .

25 The arm h is provided with a crank, h^1 , having a pin, h^3 , entering a slot in the slotted cross-head n of the piston-rod n' , having a guide, n^2 , at its other end connected with the case b , and also serving as a stop for the arm h . The piston-rod n' extends into the regulating-cylinder f , and is connected with the piston o , having one or more ports or passages, 7, controlled by a valve, p , shown in this instance as a flexible disk connected near its middle with the piston, and having its periphery overlying the ports.

By having the piston-rod act upon the lateral crank on the oscillating arm h it is possible to have the regulating-cylinder with its axis substantially parallel with the door-frame, instead of at right angles thereto, as would be required if the said piston-rod were connected directly with the arm h .

The cylinder f is provided with an opening, 8, through which it is filled with a fluid, preferably oil or glycerine, to retard the movement of the said piston. When the arm h is moved in the direction of the arrow 4 in opening the door, the piston moves 45 through the cylinder from the position shown in Fig. 2, and the liquid within it then passes freely through the ports 7, forcing the valve p open; but when the piston begins to move 50 in the other direction, under the action of the spring a , turning the arm h in the direction opposite to the arrow 4 in closing the door, the valve closes and the fluid no longer has a 55 passage through the piston, but is forced about from one to the other end of the cylinder 60 through a small passage, r , connecting the ends of the cylinder.

The end of the cylinder toward which the piston moves while the door is closing is provided with a series of small ports, 6, at different 65 distances from its end, and all in line with one another, so that their amount of

opening may be controlled by a single valve, s , operated by a handle, t , at the rear end of the cylinder, to govern the flow of the liquid, and thus regulate the amount of its retarding effect upon the piston and connected parts. The piston, in finishing its stroke, covers the said ports one after the other, and thus gradually cuts off the flow of the liquid, effectively checking the movement of the door, so that it is impossible for it to slam against the casing.

It will be seen, referring to Fig. 1, that when the door is nearly closed the crank h^1 is nearly at right angles to the line of movement of the piston-rod, and consequently the retarding force of the liquid then acts with maximum leverage, thus checking the movement of the door and causing it to close without slamming, and at the same time the spring a acts, through the arm or lever h , with the maximum leverage, thus having the greatest power upon the door, as is necessary to close and latch it. In the movement of the arm h , when the door is opened at about 85 right angles to the casing, the crank-pin h^3 will travel through the slotted cross-head, with the crank nearly in line with the piston-rod, which is thus at or near its dead-center, and almost powerless to resist the movement 90 of the arm h under the action of the spring, and the door consequently begins to close from its wide-open position, with very little retardation from the fluid in the regulating-cylinder, and will move rapidly until nearly 95 closed.

I claim—

1. In a door - check, the spring - actuated crank-arm h , provided with the pin h^3 , combined with the piston-rod n' , provided with the slotted cross-head n , in which slotted cross-head the said pin is operable to move the piston back and forth in the regulating-cylinder, substantially as and for the purpose described.

2. The actuating - spring and mechanism for transmitting its force to the door, combined with the regulating-cylinder having a passage connecting its ends and a controlling-valve therefor, and the piston provided with ports through it and a valve controlling them, and its piston-rod operating upon the said mechanism actuated by the spring, substantially as described.

3. The actuating - spring and mechanism for transmitting its force to the door, combined with the regulating-cylinder having a passage connecting its ends and a series of ports entering the said passage at different distances from one end of the said cylinder, and a single valve controlling them, and the piston operating in the said cylinder, substantially as described.

4. The spring and arm actuated thereby with an oscillating movement, and provided with a projection and stop near its free end, combined with the toggle-levers pivoted to-

gether, and adapted to be pivotally connected with the door and arm, respectively, substantially as described.

5. The spring and arm h , actuated thereby, combined with the toggle-levers k k' , one connected with the said arm, and the lug m , connected with the door and provided with a stop, m^2 , co-operating with the other of the said levers, substantially as described.

In testimony whereof I have signed my name to this specification in the presence of two subscribing witnesses.

EUGENE I. BLOUNT.
